CASTING FURNACE

Elmer H. Berryman, San Francisco, Calif.

Application July 2, 1932, Serial No. 620,616

8 Claims. (Cl. 22—69.1)

This invention relates in general to casting furnaces and in particular to furnaces for making dental castings and the like. For purposes of illustration I shall describe its use in connection with dental castings, although it is to be noted that it can be used for many other purposes, as, for example, baking materials such as porcelain, and in the manufacture of jewelry.

In dental operations the casting process comprises the following steps:

1. Forming in wax or other plastic material a model or pattern of the object desired to be reproduced by casting.

2. Attaching to the pattern a sprue former to form a sprue for permitting the injection of the metal into the mold.

3. Enclosing the pattern together with its attached sprue former in a mass of investment material, capable of setting in a short time and of withstanding heat without substantial change in dimensions.

4. Eliminating the wax from the investment by some form of applied heat, thus freeing the mold for the introduction of the metal through the sprue.

5. Fusing the metal in a crucible-like depression in the investment which communicates with the interior mold by means of the sprue.

6. Applying pressure to the molten metal to force it into all parts of the mold to insure the production of a sharp casting. The various methods of doing this include the use of gravity, vibration, mechanical pressure, compressed air or gas, partial vacuum, centrifugal force and steam.

In the past there has been no provision made for maintaining the molten metal at a uniform temperature during the time in which it was being injected through the sprue into the mold or investment, for invariably the source of heat was removed prior to forcing the metal into the mold. This has resulted in defective castings, for, on chilling, the fused metal becomes more or less sluggish and will not strictly conform to the mold. Care must also be taken not to run the temperature of the fused metal up too high, for oxidation and volatilization take place at elevated temperatures. This changes the composition of the metal and renders it unfit for further use. Furthermore, in excessively superheating the gold or other casting material, the investment deteriorates, resulting in rough surfaces in the mold, change in form of the latter, and in some cases intimate union of the investment with the casting.

In general it is the object of my invention to provide a furnace in which dental castings can be made under the influence of a differential pressure and without any substantial or detrimental change in the temperature of the fused metal or other casting material until such material has had ample time to strictly conform to the mold.

Another object of the invention is to provide a furnace in which a casting material can be fused and made to conform to the desired mold while at all times in the presence of a substantially inert gas.

A further object of the invention is the provision of a furnace which will permit observation at all times of what is taking place within it.

Still another object of my invention is the provision of quickly attachable and detachable means for securing a dental casting ring to the floor or base of a furnace.

Another object of my invention is the provision of a furnace which can be operated under the influence of a vacuum either for melting and casting metals or for baking porcelain or other materials.

The invention possesses other features of advantage, some of which, with the foregoing, will be set forth at length in the following description, where I shall outline in full that form of my invention which I have selected for illustration in the drawings accompanying and forming part of the present specification. In said drawings I have shown one form of my invention, but it is to be understood that I do not limit myself to such form, since the invention as set forth in the claims, may be embodied in a plurality of forms.

Referring to the drawings:

Figure 1 is a side elevation of a furnace embodying the features of my invention.

Figure 2 is a vertical mid-section taken on the line 2—2 of Figure 1.

Figure 3 is a horizontal section taken on the line 3—3 of Figure 2.

Figure 4 is a vertical section taken on the line 4—4 of Figure 1.

Figure 5 is a horizontal section taken on the line 5—5 of Figure 2.

Figure 6 is an elevation of one type of casting ring which may be used in combination with my furnace.

Figure 7 is an elevation partly in section of a somewhat smaller type of casting ring.

Figure 8 is a wiring diagram illustrating how, by means of a suitable switch, a pair of heating

elements such as shown in Figure 5 can be connected either in parallel or in series, depending upon the temperature desired.

As shown in Figure 1 the features of my invention are embodied in a furnace comprising a cylindrical metallic shell 1, open at its lower end and closed at its upper end by a dome-shaped cover 2 secured thereto by any suitable means as screws 3. The shell 1 is provided with a pair of rectangular, diametrically opposed lateral extensions 4 and 5 forming compartments 6 and 7 for housing the terminals of the heating elements to be described later. Plates 8 and 9, secured to the lateral extensions 4 and 5 by means of screws 11, are used in conjunction with asbestos gaskets 12 and 13 to seal the compartments 6 and 7 from the exterior atmosphere.

As shown in Figure 1 the shell 1 is provided on one side with a vertically extending sleeve 14, tapped to accommodate set screws 15 and 16 by which it can be adjustably mounted on a post or cylinder 17.

Snugly fitted within the shell 1 is piece of refractory material 18 having formed in its base a central chamber 19 and provided with an upwardly extending bored neck 21. Disposed over this refractory material and surrounding the neck 21 is a layer of insulation 22 such as, for example, "Diatex", a material composed essentially of diatomaceous earth. A disk of refractory material 23 provided with a central bore 24 is supported on the shoulder 25 formed in the upper end of the shell 1, and serves to seal the refractory material 18 and the insulation 22 from the cover 2. Resting on a shoulder formed in the central bore 24 of the disk 23 and extending up into a central tapped opening 26 provided in the cover 2, is a piece of tubing 27, and at each end of the tubing are transparent mica or quartz disks 28 and 29. This entire assembly, which may be termed a window, is clamped in position by means of the tubular nut 31 threaded in the tapped opening 26. It is to be noted that the tube 27 and nut 31 are in line with the bore in the neck 21 of the refractory material 18, and that therefore an unobstructed view is provided from the upper side of the cover 2 to the interior of the furnace.

Two diametrically opposed pairs of L shaped iron conductors 32 pass through the refractory material 18, the insulation 22 and the refractory disk 23, and are threaded at each end to provide binding posts 33 and 34. Electric leads 35 and 36 are secured to the binding posts 34 and pass through an air tight connection 37 sealed in the cover 2. Secured to the binding posts 33 and depending therefrom are spring leaves 38 provided at their lower ends with inwardly extending keepers 39. The leaves and keepers may be advantageously made of a high heat resisting steel such as "Ascoloy". The inner ends of the keepers 39 are provided with conical sockets and extend into passageways 41 formed in the refractory material 18. A pair of heating elements 42 and 43 are suspended within the chamber 19 by means of their tapered ends which are retained in the sockets of the keepers 39. The heating elements are spaced and symmetrically disposed with respect to the bore formed in the refractory material. By so orienting the heating elements the heat generated is uniformly dissipated throughout the chamber 19, and furthermore, they do not obstruct the line of vision through the tube 27 to the chamber 19. As shown in Figure 5, the heating elements 42 and 43 may be

easily removed or replaced by merely unscrewing one or both of the plates 8 and 9.

Considerable care must be exercised in selecting a suitable material from which to make these heating elements, for they are required to operate at rather elevated temperatures. An excellent material for this purpose is the composition known to the trade as "Globar" consisting mainly of silicon carbide. The ends of the elements should be treated so as to form good conductors, while their central portions should have a sufficient resistance to furnish the required temperatures at the amperage and voltage for which the furnace is designed. One convenient method of concentrating the heat generated to a limited area is to decrease the diameter of the elements midway between their ends as shown in Figure 5. Platinum wire, which is often used for heating elements in muffles, has been found to be altogether unsatisfactory for my purposes.

Secured within the lower flanged edge 44 of the shell 1 is an annular plate 45 made of any suitable refractory material and provided on its lower surface with a pair of concentrically disposed beads 46, the purpose of which will be described later.

The inner bore of the neck 21 is connected with a source of pressure such as a pressure tank 47 by means of a pressure line 48 passing through the insulation 22 and the shell 1.

Disposed below the shell 1 (see Figure 1) and directly in line therewith is a work supporting member or pedestal 49 having a central recess 51 and formed integral with a bored stem 52. A collar 53, provided with a pair of diametrically disposed bayonet slots 54, is secured within the recess 51 by any convenient means, as, for example, a force fit. The stem 52 is formed with, or has secured thereto, a rack 55 adapted to cooperatively engage a pinion 56 journaled to a bracket 57. One end of the bracket 57 is provided with a sleeve 58 surrounding the stem 52 and serves to hold it in engagement with the pinion 56, while the other end of the bracket carries a sleeve 59 mounted on the post or cylinder 17, and is adjustably secured thereto by means of the set screw 61. The pinion 56 may be rotated by means of a handle 62 and operates to elevate the pedestal 49 to any desired position where it can then be locked by means of a cam 63. A pipe 64 connects the bore of the stem 52 with a two-way valve 65, which in turn communicates either with the atmosphere through a nipple 66, or with the vacuum cylinder 17 through a flexible hose 67. The cylinder 17 may be placed in communication with any suitable source of vacuum by means of a vacuum line 68 and is provided at its upper end with a vacuum gauge 69. A pressure-reducing valve 71 is connected in the pressure line 48 between a reduced pressure gauge 72 and a full pressure gauge 73, and the upper end of the pressure tank 47 is provided with a master valve 74. The post or cylinder 17 and the pressure tank 47 are both mounted on a base 75, which may be provided with any suitable means for securing it to a bench or table 76.

In Figure 6 there is shown a cylindrical casting ring 77 for making large castings. The upper ends of this ring is provided with a neck 78 adapted to pass through the annular plate 45 and to permit the beads 46 formed on the plate 45 to engage the asbestos gasket 79 carried on the upper face of the ring 77. It is to be noted that the engagement of the beads 46 with the gasket 79 seals the casting ring 77 to the plate 45.

The lower periphery of the ring 17 is supported upon the pedestal 49 and, as a consequence, travels with it.

A smaller casting ring 81 is shown in Figure 7 and is provided with diametrically opposed pins 82 adapted to be engaged in the bayonet slots 54 formed in the collar 53. When the pins 82 are locked in the slots 54 the lower periphery of the ring is forced into engagement with an asbestos gasket 83 carried by the pedestal 49 thereby sealing the ring to the pedestal. The pedestal 49 is then sealed to the under face of the plate 45 by elevating the pedestal until the asbestos gasket 84 carried on the upper face of the pedestal is 15 pressed against the beads 46 of the plate 45.

As shown in Figure 7 the ring 81 contains an investment 85 which has formed therein the mold or impression 86, the sprue 87 and the crucible-like depression 88. It should be borne in mind 20 in giving consideration to the operation of the furnace above described that the investment is sufficiently porous to permit the passage of gas therethrough.

The wiring diagram shown in Figure 8 discloses 25 a means whereby the heating elements 42 and 43 may be used either in parallel or in series and is thought to be self-explanatory. When the switch 89 occupies the position as shown in full lines the heating elements are placed in series, while in the 30 alternative position of the switch they are placed in parallel. The switch 89 may be of any well known type and can be conveniently located on the sleeve 14.

When used as a dental casting furnace, an investment is first made in a ring such as shown in either Figures 6 or 7, the impression 86 and sprue 87 being formed by applying heat to the investment, which thereby eliminates the wax pattern and sprue former. The investment material 40 chosen is such that its coefficient of expansion, taken in connection with the coefficient of expansion of the gold or other casting material used, substantially compensates for the slight shrinkage of the gold upon cooling. This enables 45 an inlay to be made having the identical dimensions of the wax impression. If a ring, such as shown in Figure 7, is used it is inserted within the collar 53 and locked therein by means of the bayonet and slot connection above described. As 50 a rule, it is desirable to pre-heat the furnace before inserting the investment. After the casting ring is locked in position, the pedestal 47 is elevated by means of the rack and pinion 55 and 56 until an effective seal is made between the beads 55 46 and the gasket 84. However, sometime before the furnace is closed and sealed in this manner, a small piece of gold or other casting material is placed in the crucible-shaped depression 88 formed in the upper part of the investment. The 60 window formed in the upper part of the furnace permits the operations within the furnace to be watched at all times, and therefore there is no need of providing the furnace with an expensive thermopile to indicate when the fusion point of the casting metal has been reached. It is of course to be understood that if for any reason it is desired to use a thermopile one can readily be installed without in any way changing the scope of my invention. The fusion of the casting metal can be conducted either in a vacuum or in the presence of a rarified atmosphere, which is naturally present due to the fact that the furnace 70 has been pre-heated and is maintained at elevated temperatures, or in the presence of an inert gas, such as nitrogen.

The furnace can be placed under super-atmospheric pressure by putting it in communication with the pressure tank 47. By connecting the line 48 with the vacuum cylinder 11, instead of with the pressure tank 47, the furnace can be placed under sub-atmospheric pressure. The molten metal is forced through the sprue into the mold or impression by creating a differential pressure between the exterior and interior of the investment. This differential pressure may be obtained 10 by maintaining the interior of the furnace at atmospheric pressure and the under side of the investment at sub-atmospheric pressure; by maintaining the interior of the furnace at super-atmospheric pressure and the under side of the 15 investment at atmospheric pressure, or by maintaining the interior of the furnace at super-atmospheric pressure and the under side of the investment at sub-atmospheric pressure. These several combinations can of course be obtained 20 by suitably adjusting the pressure and vacuum valves above described in a manner well known to the art.

It will therefore be seen that my furnace has been particularly designed to operate for any purpose whatsoever at any desired pressure, super-atmospheric, atmospheric or sub-atmospheric. Melting and casting under a vacuum has some decided advantages in dental work, for, in the first place, oxidation of the metal and its consequent change in composition is prevented; and, in the second place, the resulting castings are free 25 of occluded gases, and as a result are more dense and conform more strictly to their patterns.

The melting operation can be carried on in a 30 non-oxidizing atmosphere and under super-atmospheric pressure by filling the tank 47 with an inert gas such as nitrogen, displacing the air contained within the furnace by suitably adjusting the various valves and then closing all of the 35 valves except those on the pressure line 48. When the casting metal has become molten it can be forced into the mold by simply opening the valve 40 65 to atmosphere.

The window permits the operations within the 45 furnace to be watched at all times, and enables the operator to determine when the metal has become molten and is ready for casting. The casting operation can be effected in any of the 50 ways above described without decreasing the temperature of the metal below a point where it tends to become sluggish. This is made possible by having the investment sealed within the furnace during the entire operation of melting and casting and maintaining the temperature within 55 the furnace above the fusing point of the metal.

The operation of the furnace under a vacuum has been found to be advantageous for baking porcelain, the resulting product being denser and more elastic than porcelain baked in the ordinary way. Porcelain baked in my furnace under the influence of a vacuum has a glazed appearance, while porcelain baked under identical conditions, with the exception that the process is carried on under atmospheric pressure, has a 60 porous appearance and is far more brittle.

When the casting or baking operation is complete, the pedestal can be lowered by means of the rack and pinion and the material removed either as a finished product or for further treatment.

It will be seen from the above description that I have provided a furnace which can be readily and effectively sealed from the atmosphere, and which can be operated under the influence of 75

any type of differential pressure. The provision of a window permits the operations within the furnace to be under observation at all times, and the bayonet and slot connection between the casting rings and the furnace pedestal affords a means for making a quick and effective seal between these two members. This latter feature is of considerable importance for it materially cuts down the time of operation. The heating elements are effectively located with respect to the material under treatment, and, at the same time, do not obstruct a direct view of the material. Furthermore, they are readily accessible.

I claim:

15. 1. A casting furnace comprising a chamber of refractory material having an open side; a heating element supported within the chamber; work supporting means adapted to be brought into registration with the open side of said chamber; means for sealing a casting ring against said work supporting means; and means for sealing the work supporting means against the open side of the chamber to form a substantially hermetic furnace.
20. 2. A casting furnace comprising a chamber of refractory material having an open side; a heating element supported within the chamber; work supporting means adapted to be brought into registration with the open side of said chamber; a casting ring adapted to be sealed against said work supporting means by a bayonet and slot connection; and means for sealing the work supporting means against the open side of said chamber.
25. 3. A furnace comprising a metallic shell provided with lateral compartments; a chamber of refractory material accommodated within said shell and having an opening in its lower side; a heating element located within said chamber and having its terminals disposed adjacent said lateral compartments; means for sealing said lateral compartments; work supporting means adapted to be brought into registration with the open side of said chamber; and means for sealing said work supporting means against the open side of said chamber.
30. 4. A furnace comprising a chamber of refractory material having an open side; a heating element located within said chamber and having its terminals engaged in keepers secured adjacent the outer surface of said chamber; a shell surrounding said chamber and provided with openings adjacent said keepers; closures for sealing said openings; work supporting means adapt-

ed to be brought into registration with the open side of said chamber; and means for sealing said work supporting means against the open side of said chamber.

5. A furnace comprising a metallic shell provided with lateral compartments; a chamber of refractory material accommodated within said shell and having an open side; keepers secured to the outer surface of said chamber and adjacent said lateral compartments; a pair of spaced 10 heating elements located within said chamber and having their terminals resiliently engaged within said keepers; closures for sealing said lateral compartments; work supporting means adapted to be brought into registration with the 15 open side of said chamber; means for sealing said work supporting means against the open side of said chamber; and a window in line with said work supporting means through which the operations within the chamber may be observed. 20

6. A furnace comprising a chamber of refractory material provided with an opening in its lower side; a pair of spaced heating elements symmetrically supported within said chamber with respect to said opening; a pedestal associated with said chamber and adapted to be sealed against its lower open side; a socket formed in said pedestal and provided with bayonet slots; a casting ring seated in said socket and provided with bayonet pins adapted to be engaged in said 25 bayonet slots; a conduit communicating with said pedestal and means for creating a differential pressure between said chamber and said conduit. 30

7. An air-tight furnace of the character described comprising a chamber of refractory material having an opening in one side; a heating element disposed within said chamber; a cover detachably sealed against said opening and itself provided with an opening for establishing communication between the interior and exterior 40 of the furnace and means for securing a casting ring to the interior face of said cover in registration with the opening therein. 45

8. A casting furnace comprising: an air-tight chamber of refractory material having an open side; a heating element supported within the chamber and across its open side; work supporting means adapted to be brought into registration with the open side of the chamber; and means for sealing said work supporting means 50 against the open side of the chamber to form a hermetic furnace.

ELMER H. BERRYMAN.
